CLAIM

The ornamental design for a trim for recessed lighting
fixture, as shown and described.

DESCRIPTION

FIG. 1 is a bottom perspective view of a trim for re-
cessed lighting fixture showing our new design;
FIG. 2 is a side elevational view thereof, all sides being
identical;

FIG. 3 is a top plan view thereof; and,

FIG. 4 is a bottom plan view thereof.

The frusto-conical portion of the trim is shaded with
oblique lines to indicate translucency.Fig. 1
